EXPANDING BAR

Filed July 11, 1927

By *Benjamin W. Snodgrass*
Wallace R. Lane
Atty.

UNITED STATES PATENT OFFICE

BENJAMIN WALTER SNODGRASS, OF DENVER, COLORADO

EXPANDING BAR

Application filed July 11, 1927. Serial No. 204,965.

This invention relates to expanding bars to be used in mining, and more particularly in breaking coal, rock or other material and loosening the same so that it may be brought 5 down in the working space of a coal mine without danger to the operator or others working in the mine and without injury to the roof of the mine. The old method of using blasting powder was extremely hazardous and by its use a great percentage of 10 broken coal or slack resulted. The danger of gas or coal explosion, so often attendant upon the use of blasting powder, will be, by the use of this invention, entirely eliminated. 15 One of the objects of this invention is to provide an expanding bar wherein the expansive force of the wedge is exerted at several distinct points simultaneously.

Another object of the device is to provide 20 an expanding bar in which the inner wedge bar is retracted in order to expand the outer wedge or sleeve member or members.

A still further object is to provide a novel 25 wedge member for said expanding bar.

Other objects, advantages and capabilities 30 are comprehended by the invention as will later appear and are inherently possessed thereby.

Referring now to the accompanying drawings:

Fig. 1 is a plan view of the novel form of 35 wedge bar.

Fig. 2 is a plan view of one of the outer 40 wedge members or sleeve.

Fig. 3 is a view in elevation of one of the outer wedge or sleeve members adapted to be 45 used with the form of wedge bar shown in Fig. 1.

Fig. 4 is an end view of the form of expanding bar looking in the direction of the arrows G—G.

Fig. 5 is a transverse sectional view taken 50 in a plane represented by line H—H of Fig. 1.

Fig. 6 is a transverse sectional view taken 55 in a plane represented by line J—J of Fig. 10.

Fig. 7 is a similar transverse sectional view, as Fig. 6, showing the bar in expanded relation.

Figs. 8 and 9 are end views of a segment of 60 the outer wedge member or sleeve shown in

Fig. 2, Fig. 9 being taken at the rectangular end of the outer wedge member.

Fig. 10 is a plan view of the novel form of 65 expanding bar, connected with a means for retracting the wedge bar.

Referring more particularly to the disclosure in the drawings, the novel construction of wedge bar 10 is shown as formed of a plurality of individual wedges, although the entire bar is preferably formed integral. The 70 forward end of the wedge bar is substantially circular in cross section as clearly shown in Fig. 4. From the forward end the wedge bar is gradually bevelled so that at the cross section H—H as shown in Fig. 5, it is substantially rectangular, each of the four sides being provided with a tongue or rib 9 that runs along substantially the entire length of each of the wedges.

Means suitably adapted to retract the 75 wedge bar is shown in Figs. 1 and 10. This means consists of a screw threaded member 13 suitably attached to the end of the wedge bar. A sleeve member 14 encompasses the shaft and abuts against the hub 15 of a gear wheel 16. The hub 15 is internally screw threaded so as to mesh with the screw threads on the member 13. Thus by the rotation of the gear wheel (which may be driven by any suitable means), the member 13 will be retracted. This member 13 in turn will retract the wedge bar and its sections 17, 18 and 19, and the retraction of the wedge bar will expand the outer wedge member or sleeve 80 composed of four segments 20, 21, 22 and 23, these segments merging into the substantially triangular sections 24, as shown in Fig. 9.

When the expanding bar is in its contracted position, these sections form a rectangle and the four segments form a circle. Each of the four sides of the wedge bar is provided with a tongue or rib 9 that is adapted to register or interlock with the respective grooves 11 of the outer wedge or sleeve members. The cross-section of the wedges decreases rearwardly, so that at the point of connection of the individual wedges, the cross-section will be smallest, while at the forward end of the individual wedges, the cross section will be greatest. Fig. 10 dis-

closes the novel form of expanding bar in assembled and contracted relation, and combined with the gear mechanism for retracting the inner wedge bar.

5 An important feature of the invention is that when the wedge bar is in its most retracted position, the inner or forward end of the outer sleeve member or wedge member is at all times positively supported along its 10 entire inner face by the inner wedge bar. This is of extreme importance as the inner or forward end has to do the greatest amount of work in breaking the coal or other material that is being operated upon. With its 15 outer member not supported in this manner, it would be rather easily crushed or bent out of shape, and thus necessarily the inner wedge bar could not properly position itself within the outer wedge members or sleeve. Even 20 though the outer sleeve members are not at all times supported along their entire face, this is not disastrous as coal, rock and the like, not being resilient, the unsupported parts are relieved of pressure by the working 25 or spreading portions.

It is to be understood that the means and method disclosed for retracting the bar may be supplanted by any other means or method that is capable of causing a retracting action. 30 While I have herein disclosed and upon the drawings shown an illustrative form of the invention, it is to be understood that it is not limited thereto but may comprehend other constructions, details, arrangements of 35 parts and features without departing from the spirit thereof.

I claim:

1. In an expanding bar, an inner wedge bar having its opposite sides beveled, each of 40 said sides being provided with a rib, and an outer wedge member composed of four segments, each of said segments provided with a groove adapted to engage a rib on the sides of the inner wedge bar, said outer segments 45 forming a circular shaped bar when the inner wedge bar is in its contracted position.

2. In an expanding bar, an inner wedge bar having its opposite sides beveled to form in cross section a square when said cross section is taken at any point along the bar, the 50 sides of said bar being provided with a rib, and an outer wedge member composed of four segments, each of said segments provided with a groove adapted to engage a rib on the sides of the inner wedge bar, said outer wedge forming an exterior circular shell, the 55 inner faces of which engage and are in continuous surface contact with the sides of the inner wedge bar when said bar is in its contracted position.

3. In an expanding bar, an inner member having a plurality of surfaces bevelled to 60 form a wedge bar, each of said surfaces being provided with a rib, and an outer wedge member comprising a plurality of segments,

each of said segments provided with a groove adapted to engage the ribs of said inner member, each of said segments having its edges in contacting engagement with adjacent segments to form a circular shaped bar 70 when the inner wedge bar is in its contracted position.

In witness whereof, I hereunto subscribe my name to this specification.

BENJAMIN WALTER SNODGRASS.
